UNITED STATES PATENT OFFICE.

JOSEPH FAUSSE, OF BROCKTON, MASSACHUSETTS, ASSIGNOR TO UNITED SHOE MANUFACTURING CORPORATION, OF PATERSON, NEW JERSEY, A CORPORATION OF NEW JERSEY.

MACHINE FOR ATTACHING TOGETHER PARTS OF BOOTS AND SHOES.

Application filed March 28, 1923. Serial No. 628,242.

To all whom it may concern:

Be it known that I, JOSEPH FAUSSE, a citizen of the United States, residing at Brockton, in the county of Plymouth and 5 State of Massachusetts, have invented certain Improvements in Machines for Attaching Together Parts of Boots and Shoes, of which the following description, in connection with the accompanying drawings, is a 10 specification, like reference characters on the drawings indicating like parts in the several figures.

This invention relates to machines for securing together parts of boots and shoes, 15 the illustrated embodiment of the invention being particularly adapted for use in securing shank pieces in turn shoes.

The rear portions of turn shoes are constructed in a variety of ways. In making 20 turn shoes of the kind known as sewed seat turns, the seam which attaches the upper to the sole about the periphery of the shoe from breast line to breast line is extended about the heel-seat also to attach the lining, 25 counter, and upper to the sole at the rear portion of the shoe. After such a shoe has been turned right side out, a shank piece is placed inside the shoe to cover the seam about the heel-seat and usually extends along 30 the shank at least to the break line or ball line. To this shank piece is usually secured a shank stiffener by which the proper degree of stiffness is given to the shank portion of the sole.

35 Other kinds of turn shoes are made with molded counters according to methods such, for instance, as those disclosed in United States Letters Patent to Helming No. 1,177, 516, granted March 28, 1916, and in United 40 States Letters Patent to Toothaker No. 1, 368,378, granted February 15, 1921. Such shoes also require the insertion of shank pieces similar to those employed in sewed seat turn shoes. It is a common practice to 45 insert and secure the shank pieces of turn shoes entirely by hand.

Objects of the present invention are to provide mechanism by the use of which shank pieces may be quickly and conveniently 50 inserted and secured in turn shoes of various kinds, and by the use of which proper pres-

sure may be applied to hold the sole, shank piece, and the intervening parts together during this securing operation.

Features of the invention consist in the 55 provision of means for applying upward pressure to the shoe bottom, together with fastening inserting means normally in a forward position to permit the shoe to be placed over it and movable rearwardly with the 60 shoe to a position over the pressure applying means so that pressure may be applied to press the sole, the shank piece, and the parts of the shoe located between them, firmly together, the fastening inserting means being then operated to fasten the shank piece in the shoe. Preferably and as shown, means is provided on the fastening inserting mechanism to hold a shank piece in position with 65 respect thereto so that the shoe may be placed 70 over the shank piece and the fastening inserting mechanism prior to movement of the shoe and fastening mechanism toward the pressure applying means. The shank piece holding means may comprise spring clips 75 the ends of which are turned inwardly to engage under the shank piece, the clips being arranged to yield vertically when the pressure is applied.

In order to locate the shoe properly with 80 respect to the shank piece, there is provided a device to engage the rear end of the shoe as the shoe and the shank piece are moved rearwardly, the device causing movement of the shoe to be arrested so that the shank piece 85 may be pushed into its proper position at the rear end of the shoe. The device is preferably arranged, as shown, to yield to rearward pressure of the shoe after the shank piece has been brought into proper relation to the 90 shoe.

These and other features of the invention, including novel constructions and arrangements of parts, will appear more fully from the following detailed description when read 95 in connection with the accompanying drawings and will be pointed out in the appended claims.

In the drawings,

Fig. 1 is a side elevation of a machine 100 embodying the present invention;

Fig. 2 is a detail, partly in section, of the

lower portion of the fastening inserting mechanism in operative relation to a shoe conventionally represented in section;

Fig. 3 is a detail in perspective of parts 5 of the tack holding means;

Fig. 4 is a plan view of the parts shown in Fig. 3 in assembled relation;

Fig. 5 is a plan view of a shank piece showing the location of the means for holding the shank piece on the fastening inserting mechanism and the location of the tracks by which it is fastened in the shoe; and

Fig. 6 is a sectional detail of parts shown in Fig. 2.

Referring to Fig. 1 of the drawings, the machine comprises a frame or column 2 upon the front side of which is arranged a vertically movable presser or support 4 for applying upward pressure to the shoe. The presser is mounted on the upper end of a rod 6 arranged to slide longitudinally in bearings 8 and 10 on the frame 2. To the lower end of the rod is pivoted a link 12 which is also pivoted on an arm 14 of an angle lever pivoted at 16 to the frame, the other arm 18 of the lever being formed as a treadle. The link 12 and the arm 14 constitute a toggle which may be straightened by depression of the treadle to cause the rod 6 and the presser 4 to be raised. The bent position of the toggle, and hence the lower position of the presser 4, is limited by a stop screw 20 threaded through the frame in position to be engaged by the toggle near its joint when in broken position, in which position it is normally held by a spring 22 connected between the frame and the arm 14.

In vertical alinement with the presser 4 is a shaft 24 mounted in bearings on the frame 2. Upon the shaft 24 a member 26, forming the casing of the fastening inserting mechanism, is arranged to swing from the position shown in Fig. 1 to a position in vertical alinement with the presser 4 and is held normally in the position shown by a coil spring 28 of the torsion type, one end of which is fixed and the other end arranged to engage a pin 30 on the fastening inserting means. At 31 are engaging faces formed respectively on the frame 2 and on the casing 26 by which outward swinging movement of the casing under the influence of the spring 28 is limited. Within the casing 26 is arranged a plunger 32 which is normally sustained by a spring 34. Upon the lower end of the plunger is a head 36 to which are secured three drivers 38 by which three tacks may be driven simultaneously. Upon the upper end of the plunger 32 is a roll 40 which is arranged to be engaged by a suitable cam 42 fixed to the shaft 24. The shaft 24 carries loosely a pulley 44 and between the pulley and the shaft is arranged a suitable

one-revolution clutch to cause a single revolution to be imparted to the cam 42 when desired. The clutch may be arranged to be tripped by downward movement of a link 46 which is connected to one arm 47 of an angle lever pivoted to the frame at 48 and having on its other arm a handle 50 arranged in a convenient position for manipulation by the operator to set the clutch and cause a single revolution to be given to the cam 42 and hence a single driving stroke to the plunger 32. The lower end of the casing 26 is provided with a driver block 51 having passages 37 in which the drivers 38 are located. Tack tubes 52 are arranged to convey tacks into ducts leading into the driver passages below the drivers. The upper parts 53 of the tubes 52 are flexible to permit swinging movement of the casing 26. Tacks are supplied to the tubes 52 in any convenient manner, for instance, from a tack pot 55 by raceways and separators of the usual type, as indicated at 57 in Fig. 1.

To hold the tacks fed to the driver passages in position to be driven and to prevent their falling out, the tack holding mechanism shown in Figs. 3 and 4 is provided. Two members 54 and 56 are secured by screws 58 to the block 51 at the lower end of the casing 26, the inner sides of the said members being rabbeted to receive complementary formations on the outer faces of the arms of a U-shaped member 60. The inner faces of the arms of the U-shaped member 60 are rabbeted to receive complementary formations on the shank portion of a T-shaped member 62, the ends of the head of which are arranged to engage the rabbets of the members 54 and 56. The members 54 and 56 are connected at their forward ends by a bar 64, there being a space between the head of the T-shaped member and the bar, as shown in Fig. 4, to permit movement of the T-shaped member relatively to the U-shaped member. The T-shaped member 62 is bored at 65 to receive a spring 66 the front end of which engages the bar 64 and serves to hold the members 60 and 62 in the position shown in Fig. 4. At the points 68, 69 and 70, between the U-shaped member 60 and the T-shaped member 62 and formed half in one member and half in the other, are conical recesses which form tack receiving pockets, these pockets of course being located beneath the ends of the driver passages 37 in the block 51. When the drivers descend to drive the tacks the T-shaped member may move relatively to the U-shaped member against the spring 66 to permit the passage of the tacks and drivers. The U-shaped member 60 is held in longitudinal position by a dowel pin in the block 51 which enters a hole 72 in the member 60. The casing 26 and the

tack holding mechanism just described are shaped peripherally to correspond substantially to the shape of the rear end of a shoe and hence, of course, to the shape of the shank piece which is to be inserted in the shoe. The shank engaging or lower face of the parts shown in Fig. 4 is preferably convexed and the co-operating face of the presser 4 concaved so that the shoe parts, including the shank piece and the sole which are clamped between them, will be given the proper exterior and interior contours desired for the inner and outer heel-seat portions of the shoe.

In order to hold the shank piece temporarily in proper relation to the fastening inserting mechanism, clips 74, 75, 76 and 78 are provided. The clips 74, 75 are similar in construction and are located one on each side of the fastening inserting mechanism and have inturned ends to engage below a shank piece at points adjacent to the breast line of the shoe. These clips 74 may be in the form of leaf springs secured by screws 80. The clips 74, 75 can therefore yield laterally to permit the shank piece, after its attachment, to be removed with the shoe. In order that the vertical pressure applied to the shoe by the support 4 may not dislocate or bend the clips 74, 75, they are arranged for vertical bodily yielding movement. The screws 80 therefore do not attach the clips 74, 75 directly to the casing 26 but to a block 82 (Fig. 6) arranged for vertical movement relatively to the casing, the amount of this movement being indicated by the space 83. The block 82 is held in place by a pin 84 passing vertically through the block 82 and held therein by a set screw 86, the projecting ends of the pin 84 sliding in holes in the casing 26. The block 82 is counterbored to receive a spring 88 arranged on the pin 84 between the block 82 and the casing 26 which holds the block 82 in its lower position and permits the block and the attached clips 74, 75 to yield vertically to upward pressure. At the rear end of the casing 26 are similar clips 76 and 78 which may be formed as branches of a single spring member 89 secured at 90 to a part 91 arranged for slight vertical movement on the casing by collared screws 92, 93 passing through slots in the part 91 and threaded into the casing. A spring 94 is arranged between the part 91 and the casing to hold the part 91 and the attached clips 76, 78 in lowered position. These clips are arranged to engage the shank piece substantially at the corners of the heel-seat as indicated in Fig. 5.

A pressing device is arranged to engage the rear portion of the shoe as it is brought into position to be operated upon and comprises a U-shaped member 96 to engage the

rear end of the shoe. The member 96 is mounted on a stem 98 arranged to slide forwardly and rearwardly in the frame 2 and held in its forward position by a spring 100, its forward position being adjustably determined by nuts 102 threaded on the stem 70 98 and normally engaging the frame.

In the use of the machine the operator takes a shank piece 6 and introduces it by endwise movement above the inturned ends of the clips 74, 75, 76 and 78, and against the lower face of the tack retaining mechanism, tacks having been fed to the tack pockets during a previous operation of the machine. The operator then takes a shoe into which a shank piece is to be inserted and places it over the shank piece and the lower end of the fastening inserting mechanism and moves the said mechanism on the shaft 24 as a pivot and against the spring 28 to bring the shoe against the pressing device 96 and over the presser 4. When the shoe engages the device 96 it is yieldingly pressed forwardly so that continued rearward movement of the shank piece and the fastening mechanism will bring the shank piece into contact with the shoe at the rear end thereof. If this contact occurs before the movement of the tacking mechanism, as determined by a stop screw 104 on the frame, is completed, the shoe may be moved farther rearwardly against the spring 100. The treadle 18 is now depressed to apply upward pressure to the shoe to force it against the tack inserting mechanism and cause the shank piece, the sole of the shoe, and the parts located between them, to be firmly pressed together and given the proper heel-seat contour as determined by the pressing faces. The handle 50 is then operated to cause power actuation of the cam 42, which acts upon the roll 40 on the upper end of the plunger 32, to cause the plunger and drivers to be depressed and the tacks to be driven through the shank piece and into the shoe. The pressure of the support 4 is released, the shoe and casing 26 swung out, and the shoe and attached shank piece removed, the clips 74, 75, 76 and 78 yielding laterally to permit passage of the shank piece by them and being restored, of course, by their springs 88 and 94 to lowered position to receive another shank piece.

Having thus described my invention, what I claim as new and desire to secure by Letters Patent of the United States is:

1. In a machine of the class described, the combination of a work support, fastening inserting mechanism having a work receiving position out of the way of the support and movable with the work to position the work over the support, and means for relatively moving the support and fasten-

- 4
- ing inserting mechanism to clamp the work during the operation of the fastening inserting mechanism.
2. In a machine of the class described, means for applying pressure to a shoe bottom, a depending fastening mechanism adapted to be inserted in a shoe and movable into and out of position over the bottom pressing means, means for operating the pressing means to press the shoe against the fastening mechanism, and means for operating the fastening mechanism.
3. In a machine of the class described, a movable fastening means adapted to receive and hold fastenings, means on the fastening means adapted to hold a shank piece in predetermined relation to the fastenings, a bottom presser over which the fastening means is movable, means for operating the pressing means, and means for operating the fastening means.
4. In a machine of the class described, the combination of means for holding a shank piece in such position that a shoe right side up may be placed over it, means for pressing the shank piece and shoe sole together, and means for inserting fastenings through the shank piece and sole while they are pressed together.
5. In a machine for inserting shank pieces in turn shoes, sole pressing means, means for holding a shank piece right side up to receive a shoe, the shoe and holder being movable to bring the shoe into proper relation to the sole pressing means, and means for inserting fastenings through the shank piece to hold it in the shoe while under pressure.
6. In a machine for attaching shank pieces to shoes, the combination of a vertically movable presser for engaging the bottom of a shoe, a tacking mechanism arranged to swing into and out of vertical alinement with the presser, means on the tacking mechanism to hold a shank piece, the shoe being placed over the shank piece and tacking mechanism and then moved with the tacking mechanism into position over the presser, and means for operating the presser and the tacking mechanism.
7. In a machine of the class described, the combination of a work support, fastening mechanism, means for yieldingly holding the fastening mechanism out of operative position with relation to the support so that a shoe may be placed over the fastening mechanism and the shoe and fastening mechanism moved into operative position over the support, means for relatively operating the fastening mechanism and support to press the shoe and fastening mechanism together, and means for inserting the fastenings.
8. In a machine for securing shank pieces in shoes, the combination of a shoe sup-
- port, fastening mechanism, means for yieldingly holding the fastening mechanism out of operative position with relation to the support, means for temporarily holding the shank piece to the fastening mechanism so that the shoe may be placed over the shank piece and the fastening mechanism, the shoe, shank piece and fastening mechanism being movable into position over the support, means for relatively operating the fastening mechanism and the support to press the shank piece, the sole and the parts between them together, and means for inserting fastenings to secure the shank piece and the sole to each other.
9. In a machine of the class described, means for inserting tacks downwardly, pockets to hold the tacks until driven, clips on the tacking means to hold a shank piece in proper relation to the tack pockets, and means for holding a shoe pressed against the shank piece while the tacks are being inserted.
10. In a machine of the class described, an upwardly movable presser, tacking mechanism movable horizontally into and out of position over the presser, and means on the tacking mechanism to hold a shank piece.
11. In a machine of the class described, the combination of a cam shaft, a casing mounted to swing on the shaft, a plunger in the casing, said plunger carrying drivers, means for holding fastenings beneath the drivers, and a cam on the shaft for operating the plunger.
12. In a machine of the class described, the combination of a work support, fastening inserting mechanism arranged to insert fastenings downwardly into the work and having a work receiving position out of the way of the support, said fastening mechanism being movable with the work to position the work over the support, and means for relatively moving the support and fastening inserting mechanism to clamp the work during the operation of the fastening inserting mechanism.
13. In a machine of the class described, means for applying upward pressure to a shoe bottom, a depending fastening mechanism adapted to be inserted in a shoe and movable horizontally into and out of position over the bottom pressing means, means for operating the pressing means to press the shoe against the fastening mechanism, and means for operating the fastening mechanism.
14. In a machine of the class described, a movable fastening means adapted to receive and hold fastenings, means on the fastening means adapted yieldingly to hold a shank piece in predetermined relation to the fastenings, a bottom presser over which the fastening means is movable, means for operating the pressing means, and means for op-

erating the fastening means, the yielding holding means permitting the shank piece to be pulled away from the fastening mechanism with the shoe after the shank piece has 5 been secured to the shoe.

15. In a machine of the class described, the combination of means for sustaining a shank piece in such position that a shoe may be placed under it, means for pressing 10 the shank piece and the shoe sole together, and means for inserting fastenings to hold the shank piece and shoe together.

16. In a machine for inserting shank pieces in turn shoes, sole pressing means, 15 means for holding a shank piece right side up to receive a shoe, the shoe and holder being movable to bring the shoe into proper relation to the sole pressing means, means in the path of the shoe to retard movement 20 of the shoe and permit the shank piece holder to move the shank piece against the rear end of the shoe, and means for inserting fastenings through the shank piece to hold it in the shoe while under pressure.

23. 17. In a machine for attaching shank pieces to shoes, the combination of a vertically movable presser for engaging the bottom of a shoe, a shaft, a tacking mechanism arranged to swing on the shaft into and 30 out of vertical alignment with the presser, means on the tacking mechanism to hold a shank piece, the shoe being placed over the shank piece and tacking mechanism and then swung with the tacking mechanism 35 into position over the presser, and a cam on the shaft for operating the tacking mechanism.

18. In a machine of the class described, the combination of a work support, fastening mechanism normally out of operative 40 position with relation to the support so that a shoe may be placed over the fastening mechanism, the fastening mechanism being movable with the shoe into operative position 45 over the support, yielding means in the path of the shoe so moved to set the shoe forwardly with respect to the fastening mechanism, means for relatively operating the fastening mechanism and support to press the shoe and fastening mechanism together, and means for inserting the fastenings.

19. In a machine for securing shank pieces in shoes, the combination of a shoe support, fastening mechanism, means for yieldingly holding the fastening mechanism out of operative position with relation to the support, means for temporarily holding the shank piece to the fastening mechanism so 50 that the shoe may be placed over the shank piece and the fastening mechanism, the shoe, shank piece and fastening mechanism being movable into position over the support, means for operating the support to 55 press the shank piece, the sole and the parts 60

between them together, and means for inserting fastenings downwardly to secure the shank piece.

20. In a machine of the class described, means for inserting tacks downwardly, 70 pockets to hold the tacks until driven, clips on the tacking means to hold a shank piece in proper relation to the tack pockets, said clips being arranged for vertical yielding movement, and means for holding a shoe 75 pressed against the shank piece while the tacks are being inserted.

21. In a machine of the class described, an upwardly movable presser, tacking mechanism movable into and out of position 80 over the presser, means for holding a tack in the tacking mechanism in position to be driven, and means on the tacking mechanism to hold a shank piece in proper relation to the tacking mechanism until the tack 85 is driven.

22. In a machine of the class described, the combination of a cam shaft, a casing mounted to swing on the shaft, a plunger in the casing, said plunger carrying drivers, 90 a cam on the shaft for operating the plunger, a presser over which the casing swings, means for raising the presser, and means for operating the cam to impart a single driving movement to the plunger.

23. In a machine of the class described, the combination of a shoe support, fastening inserting mechanism movable with the shoe to position the shoe over the support, means on the fastening means for holding a shank piece, and means for relatively moving the support and fastening inserting mechanism 100 to clamp the work during the operation of the fastening inserting mechanism.

24. In a machine of the class described, means for applying pressure to a shoe bottom, a depending fastening mechanism adapted to be inserted in a shoe and movable into and out of position over the bottom pressing means, clips on the fastening mechanism for yieldingly holding a shank piece thereon, means for operating the pressing means to press the shoe against the fastening mechanism, and means for operating the fastening mechanism.

25. In a machine of the class described, a movable fastening means adapted to receive and hold fastenings, clips on the fastening means comprising resilient strips with inturned ends to hold a shank piece in 110 predetermined relation to the fastenings, a bottom presser over which the fastening means is movable, means for operating the pressing means, and means for operating the fastening means.

26. In a machine of the class described, the combination of means comprising clips having inturned ends for holding a shank piece in such position that a shoe right side up may be placed over it, said clips being 115 120 125

mounted for yielding vertical movement, means for pressing the shank piece and shoe sole together, and means for inserting fastenings through the shank piece and sole 5 while they are pressed together.

27. In a machine for inserting shank pieces in turn shoes, sole pressing means, upwardly yielding clips for holding a shank piece right side up to receive a shoe, the shoe 10 and holder being movable to bring the shoe into proper relation to the sole pressing means, and means for inserting fastenings through the shank piece to hold it in the shoe while under pressure.

15 28. In a machine for attaching shank pieces to shoes, the combination of a presser for engaging the bottom of a shoe, a tacking mechanism movable into and out of vertical alinement with the presser, means on the

20 tacking mechanism to hold a shank piece and arranged to yield heightwise of the shoe and in the plane of the shank piece, the shoe being placed over the shank piece and tacking mechanism and then moved with the tacking 25 mechanism into position over the presser, and means for operating the presser and the tacking mechanism.

29. In a machine of the class described, drivers for inserting tacks downwardly, relatively movable members having in their 30 meeting edges recesses formed part in one

member and part in the other member to constitute pockets to hold the tacks until driven, clips on the tacking means to hold a shank piece in proper relation to the tack pockets, and means for holding a shoe pressed against the shank piece while the tacks are being inserted.

35 30. In a machine of the class described, an upwardly movable presser, tacking mechanism movable horizontally into and out of position over the presser including tack holding means comprising members having meeting edges alined with the tack locations, said edges being recessed at opposite points to form tack pockets, means for holding said edges yieldingly together, and means on the tacking mechanism to hold a shank piece in predetermined relation to the tack pockets.

40 31. In a machine of the class described, the combination of a cam shaft, a casing mounted to swing on the shaft, a plunger in the casing, said plunger carrying drivers, means for holding fastenings beneath the drivers, a cam on the shaft for operating the plunger, a presser, a toggle for raising the presser, and a clutch for imparting a single revolution to the cam.

45 In testimony whereof I have signed my name to this specification.

50 JOSEPH FAUSSE.
